CURLING IRON AND PRESSING COMB
HEATER

Winfred M. Patton, Chicago, Ill.

Application April 12, 1946, Serial No. 661,810

2 Claims. (Cl. 126—229)

1

This invention relates to a novel construction of heaters for curling irons and pressing combs and has for its primary object to provide an improved construction of heater of the type utilizing a liquid fuel.

An important object of the invention is to provide an elongated, rectangular burner which is so constructed as to enable the heat to be concentrated under the curler or comb to be heated.

A further object of the invention is to provide an improved construction of chimney which will function to produce a ribbon of flame substantially co-extensive with the burner wick for uniformly heating the curler or comb throughout its length.

Still a further object of the invention is to provide a heater having a novel chimney construction including multiple flue outlets located so as to concentrate the heat of the burner in proximity to the item to be heated and which will increase the height of the flame, when a curling iron or pressing comb is in position on the heater, to thereby increase the heating efficiency of the burner.

Still a further object of the invention is to provide a burner of the above described characteristics which is of a very simple construction and capable of being readily assembled or disassembled and which is so constructed that it may be easily lighted.

Numerous other objects and advantages of the invention will hereinafter become more fully apparent from the following description of the drawing, which illustrates a preferred embodiment thereof, and wherein:

Figure 1 is a perspective view of the heater;

Figure 2 is a longitudinal, substantially central sectional view, partly in side elevation thereof; and

Figure 3 is a cross-sectional view of the heater taken substantially along the plane as indicated by the line 3—3 of Figure 2.

Referring more particularly to the drawing, the heater, constituting the invention, is designated generally 5 and includes an elongated base 6 which is provided with an open bottom, as best seen in Figure 3 and which has depending supporting legs 7 at the corners thereof. Super-imposed upon the base 6, and forming a part thereof when the heater 5 is assembled, is an outer chimney 8 which is relatively long, high and narrow and which is open at its top and bottom. As best seen in Figure 3, the side walls 9 of the base 6 form continuations of the lower ends of the side walls 10 of the outer chimney 8 and said side walls 9, 10 converge slightly from their lower to their upper ends. The outer chimney 10 is connected by means of hinges 11 along one of its side walls 10, at the

2

lower edge thereof, to the base 6, along one upper edge of one of its walls 9. The side walls 9 of the base 6 are provided with inturned flanges at the ends thereof which are provided with overlapping portions connected by fastenings 12 to form the end walls 13 thereof. The side walls 10 of the outer chimney 8 are provided with similar inturned flanges at their ends having overlapping portions which are detachably connected by a fastening member 14 to form the end walls 15 of the chimney 8. A burner 16 is mounted in the base 6 and is supported by brackets 17 which are welded or otherwise secured to the ends thereof and to the complementary flanges, forming parts of the end walls 13, which project from one of the side walls 9. The burner 16 is provided with a wick receiving recess 18 which extends substantially the length of the burner 16 and having a bottom 19 onto which the fuel is admitted. The receiver 18 is provided to receive an elongated wick 20 having a lower edge depending into the bottom 19 and an upper edge which opens into an elongated burner trough 21, forming the top of the burner 16, and best seen in Figure 3.

The wick 20 is stationary and height of the flame is controlled by the amount of fuel admitted to the bottom 19. The burner 16 is heated to a high temperature by the flame so that the fuel is converted to a gaseous state almost immediately upon entering the burner 16. The gaseous fuel keeps the wick 20 saturated and the extent of its saturation governs the size of the flame.

A substantially cup-shaped holder 29, provided with a well 30 in the bottom thereof, is provided to support an inverted tank 31 which is mounted therein and which is retained in place by a bayonet connection 32. The tank 31 is adapted to be filled with a suitable liquid fuel, not shown, and is provided with a restricted outlet, now shown which is open when the tank 31 is supported in an inverted position in the holder 29 so that the fuel may flow from the tank 31 into the well 30 in a manner conventional in liquid fuel burners. A pipe 33 has one end extending through an end of the well 30 and in communication with the interior thereof and its opposite, discharge end extends through the adjacent end of the sump 18 and opens into the interior thereof for supplying the liquid fuel thereto. The pipe 33 is provided with a shut-off valve 34, located intermediate of its ends. The valve 34 may be of any conventional construction, preferably a needle valve, and functions to regulate the amount of fuel supplied to the burner 16, to thus regulate the size of the flame, as previously described.

An inner chimney 35 is located within the outer chimney 8 and is disposed in an upright

position with its open lower end extending into and resting on the burner well 21, as best seen in Figure 3. The inner chimney 35 is provided with an open top which is disposed some distance below the open upper end of the outer chimney 8. The chimney 35 is elongated and substantially rectangular, looking from top to bottom thereof, and is spaced inwardly from the side walls 10 and end walls 15, as seen in Figures 2 and 3. The end walls of the chimney 35 are closed but the side walls thereof are provided with a plurality of apertures 36. The fastening 14 extends lengthwise through the chimney 8 and chimney 35 and a similar fastening 31, formed of a length of rod or wire, extends transversely through the chimneys 8 and 35 to combine with the fastening 14 to demountably support the chimney 35 in a correct position within the chimney 8.

The side walls 9 of the base 6 are each provided with a row of openings 38 which open into the base 6 at the sides of the holder and well 16. Said walls 10 are provided with outwardly flared upper edge portions 39 and are provided with horizontal series of openings 40 located directly beneath the flared portions 39. The end walls 15 are provided with concave upper edges 41 which combine with the flared portions 39 to form a holder or receiver for a curling iron or pressing comb, not shown, which is adapted to be supported lengthwise thereon so as to substantially close the open top of the burner 5, defined by the portions 39 and 41.

To light heater 5, the valve 34 is opened to admit fuel to bottom 19 so that the wick 20 will be saturated, after which the chimney 8 is swung on the hinges 11 outwardly and downwardly to a horizontal position to provide access to the wick 20 so that it can be readily lighted. The inner chimney 35, being supported by the outer chimney 8 by means of the members 14 and 37, will be carried with the chimney 8 so as to expose the open top of the base 6 and the burner well 21. The chimneys 8 and 35 are thereafter returned to their normal position, as illustrated in the drawing. A curling iron or pressing iron, not shown, is then placed lengthwise on the open top of the chimney 8 to be heated by the flame from the wick 20. Air will enter the base 6 between the legs 7 and through the openings 38 and will enter the inner chimney 35 through the openings 36 in the two sides thereof, so as to supply a substantially uniform amount of air to the upper edge of the wick 20 throughout its length. By this means, substantially uniform burning of the wick, throughout its length, is assured. The openings 40 form flue outlets for the products of combustion from the flame and are arranged adjacent to the article to be heated and in the top part of the burner 5 so as to draw the flame upwardly in the inner chimney 35 to produce the maximum amount of heat at the point where the heat is to be utilized. It has been discovered that by providing the openings 36 throughout the side walls of the inner chimney 35 that the air will be admitted to the flame both above and below the flame thereby tending to draw the flame upwardly and toward the article to be heated thus reducing the length of time required to effect the heating. Further, the article to be heated by substantially closing the open top of the burner cooperates with the flue outlet 40 and the apertures 36 in producing a higher flame than that which results when the top of the burner 5 is left open.

Various modifications and changes are contemplated and may obviously be resorted to without departing from the spirit and scope of the invention as hereinafter defined by the appended claims.

I claim as my invention:

1. A curling iron and pressing comb heater comprising an upright burner casing of elongated rectangular shape in cross section, said burner casing tapering in width uniformly from the bottom to the top thereof and including a base section and a chimney, said chimney resting on and being supported by and directly connected to the base section, said burner casing being open at its top and bottom, the open top of the burner casing forming a support for an article to be heated, supporting legs forming depending extensions of the lower end of the burner casing for supporting the open bottom in an elevated position, and a fuel and wick holder disposed in and supported entirely by the base section in spaced relationship to the walls of the base section whereby said burner casing provides an uninterrupted air passage around the fuel and wick holder from its open bottom to its open top and the chimney provides a flue passage between the fuel and wick holder and the open top of the burner casing.

2. A curling iron and pressing comb heater as in claim 1, an inner perforated chimney member disposed within the burner casing and supported by the chimney in spaced relationship to the walls of the burner casing, said inner chimney member engaging the fuel and wick holder when the chimney is disposed in superposed relationship relatively to the base section and being swingable with the chimney to expose the open top of the base section and the fuel and wick holder, said chimney being formed of sections having overlapping flanges provided with aligned openings, and a rod extending through said aligned openings and through the inner chimney member for detachably connecting the sections of the chimney and for detachably supporting the inner chimney member therein, one section of the chimney being hinged at its bottom edge to the upper edge of the base section for swingably supporting the chimney on the base section whereby the chimney with the inner chimney member supported thereby may be swung from an upright position upon the base section to a position to expose the upper end of the base section of the fuel and wick holder.
